ATTORNEYS.

UNITED STATES PATENT OFFICE.

WILLIAM F. GEHRIG, OF BERKELEY HEIGHTS, NEW JERSEY, ASSIGNOR TO ESSEX SPECIALTY CO. INC., OF BERKELEY HEIGHTS, NEW JERSEY, A CORPORATION OF NEW JERSEY.

PYROTECHNICAL DEVICE.

Application filed February 16, 1925. Serial No. 9,481.

To all whom it may concern:

Be it known that I, WILLIAM F. GEHRIG, a citizen of the United States, residing at Berkeley Heights, in the county of Union 5 and State of New Jersey, have invented certain new and useful Improvements in Pyrotechnical Devices; and I do hereby declare the following to be a full, clear, and exact description of the invention, such as will enable others skilled in the art to which it 10 pertains to make and use the same, reference being had to the accompanying drawings, and to characters of reference marked thereon, which form a part of this specification.

15 This invention relates, generally, to improvements in pyrotechnical devices; and the invention has reference, more particularly, to a novel pyrotechnical device in the form of a torpedo adapted to be fired by percussion.

20 The invention has for its principal object to provide a novel construction of firework torpedo adapted to be set off by percussion; and adapted, when thus ignited, 25 to produce a series or intermittent succession of detonations, thus providing a repeating torpedo of novel and pleasing effect which will operate for a comparatively long time after it is ignited.

30 Other objects of this invention, not at this time more particularly enumerated, will be clearly understood from the following detailed description of the same.

35 With the various objects of this invention in view, the same consists, primarily, in the novel repeating percussion torpedo hereinafter set forth; and, the invention consists, furthermore, in the novel arrangements and combinations of the several devices and parts, all of which will be hereinafter more fully described in the following specification, and then finally embodied in the claims appended thereto.

40 The invention is clearly illustrated in the accompanying drawings, in which:—

45 Figure 1 is a side elevation of the novel torpedo, made according to and embodying the principles of this invention; Figure 2 is a perspective view of the torpedo with the

outer cover unfolded to disclose one form 50 of pyrotechnical element; Figure 3 is a similar perspective view, with the said pyrotechnical element opened to disclose the means for igniting the pyrotechnical element by percussion; Figure 4 is a perspective view 55 of one form of pyrotechnical element; Figure 5 is a part side elevation and part section of a modified form and arrangement of pyrotechnical element and percussion producing means; and Figure 6 is a perspective 60 view and part section with the outer covering unfolded, illustrating another modified form and arrangement of pyrotechnical element and percussion producing means.

65 Similar characters of reference are employed in the above described views, to indicate corresponding parts.

Referring to said drawings, the reference character 1 indicates the complete torpedo, made according to and embodying the principles of this invention. In one arrangement, said torpedo 1 consists of a percussion producing means 2 in the form of an integral hard body or mass, such as a stone, marble or the like; wrapped around said 70 percussion producing means 2 is a combustible carrier sheet 3, preferably made of thin paper, such as tissue paper, upon which are caused to adhere a plurality of pastilles or lozenges 4, consisting of a pyrotechnical 75 composition adapted to produce detonations when ignited by percussion. It will, of course, be understood that there are many different pyrotechnical compositions known to those skilled in the art which, when thus ignited, will produce explosions or detonations, and consequently, in this respect, I do not desire to limit myself to the use of any particular composition so characterized, although I prefer to employ a composition heretofore known and used to produce intermittent detonations, and which comprises a mixture of gum-arabic, carbonate of magnesium, white phosphorus, red ocher and potassium chloride. The pastilles or lozenges 4 of pyrotechnical composition are arranged in a group upon said carrier sheet 3, the mem-

90
95

bers of which are suitably spaced apart. It is preferable to treat the paper or other carrier sheet 3 with some chemical adapted to insure continued combustion thereof once the same is ignited. A chemical such as saltpeter may be employed for such purpose, although I do not limit myself to the use of that substance for the purpose. The carrier sheet 3, with its group of detonatable pastiles or lozenges 4, is wrapped around the percussion means 2 so as to enclose the same, the same being retained in such enclosing relation, by twisting its free edges together, as at 5, or by securing said edges together in any other suitable manner. When the carrier sheet 3 and percussion means 2 are thus operatively assembled together, the same are preferably enclosed in an outer covering or jacket 6, preferably made of thin tissue paper or like material, which is caused to envelop the assembled carrier sheet 3 and percussion means 2, and which is closed by twisting its free edges together, as at 7, or by securing said edges together in any other suitable manner.

The device, constructed as above described, is ready for use, and may be discharged or ignited by throwing the same forcibly against any rigid or relatively hard surface, such, for example, as a sidewalk or pavement. When thus thrown, one or more pastiles or lozenges 4 on the carrier sheet will be interposed between the percussion means 2 and the surface against which the torpedo is thrown, and consequently will receive the impact of the percussion means, thereby discharging or igniting such pastiles or lozenges. Combustion being thus started, the pastiles or lozenges will discharge to produce a series of intermittent explosions or detonations, which, as combustion spreads throughout the carrier sheet 3, will be continued until all the pastiles or lozenges are consumed. It will, therefore, be apparent that a very novel effect is produced, and one of relatively long duration, thus making the device highly entertaining and amusing.

The same novel effects and advantages above recited may be obtained by means of somewhat modified arrangements and constructions of the torpedo. In one such modified form, which I have illustrated in Figure 5 of the drawings, the carrier sheet 3 may be omitted, and a plurality of unmounted or free lozenges or pastiles 8 of the pyrotechnical composition may be produced and mixed together with a mass of loose granular percussion material 9, such as gravel or coarse sand, in such manner that the lozenges or pastiles 8 are interspersed throughout the mass of such percussion material. The materials thus prepared are enclosed in a covering or jacket 10 of tissue paper, suitably secured in such enclosing relation. Upon throwing such modified form

of torpedo against a relatively hard surface, the impact of the percussion material 9 with the lozenges or pastiles will set off the latter, which will thereupon ignite and burn, and during combustion produce the intermittent detonations or explosions until consumed.

In another modification of my novel torpedo, I utilize the carrier sheet 3 with the group of pyrotechnical pastiles or lozenges 4 adhering thereto, but instead of employing an integral percussion means 2, such as a stone, marble or the like, I use percussion material 11 in the form of a mass of loose granular material, such as gravel, coarse sand or the like, which is enveloped by the carrier sheet when the same is suitably wrapped and secured around the mass of percussion material. I prefer to enclose the assembled carrier sheet 3 and percussion material 11 in an outer covering sheet or jacket 6, in the manner hereinbefore stated. Upon throwing the torpedo against a relatively hard surface, the pastiles or lozenges 4 will be ignited by the impact therewith of said percussion material 11, and the novel pyrotechnical effects already above described will be obtained.

I am aware that some changes may be made in the arrangements and combinations of the parts making up my novel torpedo, as well as in the details of the construction and composition of the said parts, without departing from the scope of the invention as above set forth, and as defined in the following claims. Hence, I do not limit myself to the exact arrangements and combinations of the various parts as described in the foregoing specification, nor do I confine myself to the exact details of the construction of the said parts as illustrated in the accompanying drawings.

I claim:

1. A torpedo of the kind described comprising a combustible carrier sheet having a group of separated lozenges of detonating pyrotechnical composition secured thereto, and a percussion material around which said carrier sheet is enveloped.

2. A torpedo comprising a combustible carrier sheet having a plurality of lozenges of detonating pyrotechnical composition adhering thereto, a percussion material, said carrier sheet being wrapped around said percussion material to enclose the same therein, and an outer jacketing wrapper exteriorly enveloping the assembled carrier sheet and percussion material.

3. A torpedo comprising a combustible carrier sheet having a plurality of lozenges of detonating pyrotechnical composition adhering thereto in grouped relation, a relatively hard percussion body, and said carrier sheet being wrapped around said body to enclose the same therein.

4. A torpedo comprising a combustible carrier sheet having a plurality of lozenges of detonating pyrotechnical composition adhering thereto in grouped relation, a relatively hard percussion body, said carrier sheet being wrapped around said body to enclose the same therein, and an outer jack-

eting wrapper exteriorly enveloping the assembled carrier sheet and percussion body.

In testimony, that I claim the invention ¹⁰ set forth above I have hereunto set my hand this 5th day of January, 1925.

WILLIAM F. GEHRIG.
